DESIGN FOR A FLOWERPOD ASSEMBLY

Clarence W. Jorgensen, Chicago, Ill.

Application August 26, 1940, Serial No. 94,623

Term of patent 7 years

To all whom it may concern:

Be it known that I, Clarence W. Jorgensen, a citizen of the United States, residing at Chicago, in the county of Cook and State of Illinois, have invented a new, original, and ornamental Design for a Flower Pot Assembly, of which the following is a specification, reference being had to the accompanying drawing, forming a part thereof.

In the drawing:

Figure 1 is a perspective view of a flowerpot assembly, showing my new design;

Figure 2 is a top plan view thereof; and

Figure 3 is a side elevational view.

The dominant features of the design consist in a substantially flat base member and a plurality of upstanding pegs carried by said base member and arranged in pairs in combination with flowerpots supported upon said base and between said pairs of pegs, as shown in the drawing.

I claim:

The ornamental design for a flowerpot assembly, substantially as shown and described.

CLARENCE W. JORGENSEN.
